US00D403780S

United States Patent [19]

Bishop et al.

[11] Patent Number: Des. 403,780

[45] Date of Patent: **Jan. 5, 1999

[54] WAVE ENERGY EXTRACTION MODULE

[76] Inventors: **Robert Bishop; Justin Bishop**, both of 1083 Bloomfield Ave., West Caldwell, N.J. 07006

[**] Term: 14 Years

[21] Appl. No.: 63,882

[22] Filed: Dec. 18, 1996

[51] LOC (6) Cl. 25-01

[52] U.S. Cl. D25/113

[57] CLAIM

We claim the ornamental design for a wave energy extraction module, as shown and described.

DESCRIPTION

FIG. 1 is a front perspective view of a wave energy extraction module showing our new design according to the present invention;

FIG. 2 is a left side elevational view thereof;

FIG. 3 is a right side elevational view thereof;

FIG. 4 is a top plan view, the opposite side being a mirror image thereof;

FIG. 5 is a front plan view, the opposite side being a mirror image thereof;

FIG. 6 is a front plan view of FIG. 4 pivoted approximately 45°; and,

FIG. 7 is a rear plan view of FIG. 4 pivoted approximately 45°.
